UNITED STATES PATENT OFFICE.

ALBERT T. FISCHER, OF CLEVELAND, OHIO.

VENDING-CARTON.

1,194,372.

Specification of Letters Patent. Patented Aug. 15, 1916.

Application filed December 3, 1915. Serial No. 64,803.

To all whom it may concern:

Be it known that I, ALBERT T. FISCHER, a citizen of the United States, residing at Cleveland, in the county of Cuyahoga and 5 State of Ohio, have invented a certain new and useful Improvement in Vending-Cartons, of which the following is a full, clear, and exact description.

This invention relates to a carton which 10 serves as a packing receptacle for articles and also forms a neat and attractive dispensing and vending device.

The object of the invention is to provide 15 a device made from a single blank which forms a carton having portions cut away to display the goods contained in the carton and the provision of means whereby the articles within the carton may be kept in alignment and prevented from falling forward or 20 backward.

Generally speaking the invention comprises the elements and combinations thereof set forth in the accompanying claims.

Reference should be had to the accompanying drawings forming a part of this specification, in which—

Figure 1 is a perspective view showing the carton; Fig. 2 is a transverse section on the line 2—2 of Fig. 1; Fig. 3 is a plan view of 30 the blank as cut out from a sheet of material.

The blank as cut from a sheet of cardboard or similar material, comprises a front portion 1, a back portion 2, and side portions 3 and 4. The back portion 2 has extending 35 flap portions 2^a and 2^b which are provided with slits 2^c. There are also flap portions 1^a and 1^b which are provided with cut out ears 1^c which when the carton is folded together engage with the slits 2^c. The side 40 portions 3 and 4 are provided with flap portions which fold in and lie against the flap portions of the back portion 2 and front portion 1 when the carton is folded together, as will be readily understood. The side portion 45 3 is provided with an extending tongue 3^a which folds against the back portion 2 and is secured thereto. The side portions 3 and 4 have panel-like portions 5 which are severed on three sides but left attached on one 50 side as indicated at 5^a, as will be more clearly seen in Fig. 1 and Fig. 2. The side portion 3 is provided with openings 6. In the present instance these openings are circular and three in number. The side portion 4 is provided with an opening 7 which as shown ex-

tends substantially across the side portion 4. The opening 7 is in alignment with the openings 6. The front portion 1 has open or cut away portions 1^d which permit display of the articles contained within the carton. 60 There is shown, however, a diagonally extending band 1^e which assists in retaining the articles within the carton, and also assists to retain them in proper alignment, and further prevents extraction of the articles 65 within the carton through the openings in the front of the carton.

The carton is designed to receive three rows of articles, the articles of each row being arranged in vertical alignment. Each 70 article is of a length to fit between the side portions 3 and 4. One vertical row is in contact with back portion 2, another vertical row is in contact with the front portion 1, and there is a third row which is intermediate the other 75 two rows and this third row extends between the inturned panels 5. It will be seen that the inturned panels 5 hold and maintain the vertical rows in alignment and prevent the packages falling out of alignment as articles 80 may be withdrawn from the lower part of the carton and form channels therebetween to guide the articles as they move downward toward and into registry with the opening 7. It will be seen that the lowermost articles in 85 each vertical row will be in line with the opening 7 and the openings 6, and, by inserting a finger of the hand through the opening 6, one of the articles may be pushed through the opening 7. In this manner the articles in the carton may be dispensed until all have been removed. The front vertical 90 row of articles will be observable through the openings 1^d, so that the articles to be dispensed or vended may be always in view.

Portions of the carton are adapted to receive printed matter descriptive of and advertising the contents of the articles or packages within the carton.

What I claim is:

1. A carton having a dispensing opening and means within the carton for retaining the contents in vertically aligned rows, and forming guide channels therefor, while permitting the contents to move into registry 105 with said opening.

2. A carton having a dispensing opening and partition members extending inwardly from the walls of the carton for retaining the contents in vertically aligned rows, and 110

forming guide channels therefor, while permitting the contents to move into registry with said opening.

3. A carton having a dispensing opening and partition members formed by severing portions of the walls of the carton, said partition members being folded to extend inwardly and serving to divide the contents into vertical rows and to maintain the rows in vertical alinement, and forming guide channels therefor, while permitting the contents to move into registry with said opening.

4. A carton having a dispensing opening, a plurality of panels partially cut in oppositely disposed portions of the carton, said panels being folded to extend inwardly, said panels serving to divide the contents of the box into vertical rows and to maintain the vertical rows in alinement, and forming guide channels therefor, while permitting the contents to move into registry with said opening.

5. A carton having oppositely disposed portions in one of which portions there is a dispensing opening and in the other of said portions an opening by which access may be had to the interior of the carton to push an article contained therein through the dispensing opening, said portions being provided with inwardly extending partition

members which are above the said openings in the said portions, the partition members serving to retain the articles within the carton in vertical alinement, and forming guide channels therefor, while permitting the contents to move into registry with said opening.

6. A carton having a front portion which is provided with openings whereby the articles within the carton may be seen, said carton having oppositely disposed side portions, one of said side portions being provided with a dispensing opening, the other of said sides being provided with an opening providing access to the carton whereby an article within the carton may be pushed through the dispensing opening and panels formed by partially severing portions of the said sides above the openings therein, said panels being bent inwardly along an unsevered edge, thereby forming partitions to hold the articles within the carton in vertical alinement, and forming guide channels therefor, while permitting the contents to move into registry with said opening.

In testimony whereof, I hereunto affix my signature in the presence of two witnesses.

ALBERT T. FISCHER.
